United States Patent Office.

DENNIS BUOY, OF DANVILLE, PENNSYLVANIA.

Letters Patent No. 99,148, dated January 25, 1870.

IMPROVEMENT IN WEIGHING-SCALES.

The Schedule referred to in these Letters Patent and making part of the same.

To all whom it may concern:

Be it known that I, DENNIS BUOY, of Danville, in the county of Montour, and State of Pennsylvania, have invented certain new and useful Improvements in Scales or Balances; and I do hereby declare the following to be a full, clear, and exact description thereof, reference being had to the accompanying drawing, which is made a part of this specification.

My invention relates, primarily, to counter-scales of that class which operate on the principle of the steel-yard or Roman balance; and

It consists—

First, in constructing the beam or lever with one or more graduated series of holes or cups for the reception of the weight or weights; and

Second, in attaching the dish to the beam or lever through the medium of a supplementary lever of the third order, for the purpose of removing the series of weight-holes of the beam to the desired distance from the dish, to afford convenient access to them.

In the drawing—

Figure 1 is a plan view of a counter-scale, embodying my improvements, the dish being removed.

Figure 2 is a side elevation thereof, partly in vertical section.

A hollow base, A, of suitable material and form, is employed, provided with two or more vertically-projecting arms or standards a' , to support the beam, &c., and with a number of holes, a'' , and a cup, a''' , or a corresponding series of holes or cups for the reception of the weights when not in use, a lateral extension being provided for the reception of said holes, &c., as represented in fig. 1.

A frame, B, arranged over the head of the base A, supports the dish C, and is held in its vertical position by means of the customary guide-rods b' , arranged within the base, as represented in fig. 2.

A bar or lever, D, fulcrumed at d in the standard a' , at the rear end of the base, engages with the frame B by means of the customary pivots d' , having their "knife-edge" upward, and resting in suitable sockets in the legs of said frame, and is connected at an intermediate point central between said pivots d' and the pivots e of the beam E, to the front end of said beam, by means of a pair of links, F, engaging with pivots d'' and e' on said lever and beam respectively.

The beam E is fulcrumed in the upper end of the standard a' , which is bifurcated and provided with suitable sockets for the reception of its pivots. In form it may be substantially as represented, and may be of steel, brass, or other suitable metal, or of two or more of such metals combined, as represented.

It is provided, in front of its fulcrum, with, preferably, two longitudinal series of holes, e'' e''' , or cups, for the reception of the weights, the holes in the series

being of suitable capacity to accommodate the different sizes of weights employed, of any desired number, preferably eight and sixteen respectively, and each series, if preferred, connected by a groove, to facilitate adjusting the weights therein.

The graduation is made relatively to the distance between the "pivots" of the two levers, and by properly arranging the pivots d' of the lever D, may be made relatively to the distance between the points e and e' , in approximately the same manner as were the dish supported directly at e' .

The above-described arrangement of the levers D and E presents the advantage of allowing the dish to be placed at a greater distance from the fulcrum of the scale-beam without sensibly affecting its leverage, and thus affords more convenient access to the weight-holes.

The motion of the beam E, and consequently of the other parts connected thereto, is limited by means of a downwardly-projecting link, e' , embracing a pin, a^4 , projecting rearwardly from the upper end of the standard a' , and a projection, a^5 , on top of said standard.

The balancing of the several parts is secured in the usual manner, any little inaccuracy in either direction being compensated for by means of an adjustable ball or weight, G, on the lever D, and a box or receptacle, H, for the reception of shot, &c., at the extremity of the beam E, or equivalent means.

The holes a'' e'' e''' in the base A and beam E, when such are used, flare inwardly or downwardly, as represented at a'' in fig. 2, and thus prevent any accumulation of dirt, &c., within them, and the small amount of bearing-surface for the weights, thus formed, prevents the transfer, in any appreciable quantity, of any which might be on their surface to the weights, by resting in them. This is especially desirable for the holes a'' in grocers' scales, which are constantly receiving small portions of the sugar, &c., which is being weighed.

The weights i i' i'' i''' are in the form of balls or spheres, preferably of iron or other suitable metal, polished to adapt them to readily accommodate themselves to a seat. Their size is so regulated as to represent the different denominations which it is desired to use. Those represented are intended to illustrate respectively one and one-half pound, i ; one pound, i' ; two ounces, i'' ; and one ounce, i''' ; of which, with the style of scale represented, I use one one and a half pound, two one-pound, and one each of two and one ounce, as represented.

The series of holes e'' and e''' in the beam E are for the reception of the weights i i' and i'' i''' respectively.

A pound weight, i , placed in the first hole in the series e'' , will balance one pound in the dish; in the second, two; and so on in arithmetical progression.

A two-ounce weight, i' , in the first hole in the sc-

ries e'' , (which is only one-half the distance from the fulcrum e than the first of the series e'' is,) will balance one ounce in the dish; in the second, two; and so on.

An ounce weight, i'' , in the first of the series e'' , will balance half an ounce in the dish, which is the minimum generally required in a counter-scale; in the second, one ounce; in the third, one and a half; and so on. The pound and a half weight i being one-third heavier than the one i'' , will, in similar positions, balance an increased amount in the same ratio; thus, being placed in the first of the series e'' , it will balance one and a half pound; in the second, three; in the fourth, six; and so on.

It is, however, preferably employed only in the last of said series, (where it balances twelve pounds,) with the two-pound weights i , arranged in the next two holes of the series, (balancing seven and six pounds respectively,) as represented in red outline in fig. two, to balance twenty-five pounds, which is the maximum generally required in a counter-scale. Other combinations will readily be perceived.

Instead of this precise manner of operating the scale, it is obvious that many substantially similar, and for some uses preferable, arrangements may be employed. For instance, but one weight or one size of weight

may be used, and the holes or cups in one or a plurality of series be so arranged as to indicate the weight in the different denominations; or different sizes of weights in a single series may be employed instead. The number of weights and holes or cups will, of course, be varied to suit the class of weighing the scale is intended to perform.

Having thus described my invention,

I claim as new therein, and desire to secure by Letters Patent—

1. A weight, i , constructed of spherical form, and employed in combination with a scale having a beam or lever provided with holes or cups e'' , substantially in the manner and for the purpose set forth.

2. The combination, with the weigh-beam E , constituting a lever of the first order, of the supplementary lever D , of the third order, interposed between said beam and the dish-frame, as described, for the purpose set forth.

To the above specification of my invention, I have signed my hand, this 8th day of December, 1868.

DENNIS BUOY.
